[57] CLAIM

The ornamental design for a bracket unit for price display, as shown and described.

DESCRIPTION

FIG. 1 is a front perspective view of the bracket unit for price display showing my new design in an opened position; FIG. 2 is a top plan view of one of the brackets of the new design;

FIG. 3 is a front elevational view thereof;

FIG. 4 is a side elevational view thereof, the opposite side being a mirror image; and,

FIG. 5 is a perspective view thereof, in a closed position. The bracket is shown detached from the unit in FIGS. 2-4 for ease and clarity of illustration.

The broken line showing of a price display sign is for illustrative purposes only and forms no part of the claimed design.
